UNITED STATES PATENT OFFICE.

JESSE MATTERN, OF TYRONE, PENNSYLVANIA.

RAIL-JOINT CHAIR.

1,096,178.

Specification of Letters Patent.

Patented May 12, 1914.

Application filed July 23, 1913. Serial No. 780,834.

To all whom it may concern:

Be it known that I, JESSE MATTERN, a citizen of the United States, residing at Tyrone, in the county of Blair and State of Pennsylvania, have invented certain new and useful Improvements in Rail-Joint Chairs, of which the following is a specification, reference being had to the accompanying drawings.

10 This invention comprehends certain new and useful improvements in rail joint chairs and has for its primary object to provide a rail joint chair of improved and simplified construction and which will securely grip 15 the meeting ends of rails and hold the same in position without the necessity of extending bolts or other securing means through the rails.

Another object is to provide a hinged rail 20 joint chair which will be of extremely simple construction, strong and durable, and highly efficient and effective in use, as well as cheap to manufacture.

With the above and other objects in view, 25 my invention consists in certain novel constructions, combinations, and arrangements of parts to be hereinafter more fully described, claimed, and illustrated in the accompanying drawings, in which,

30 Figure 1 is a longitudinal sectional view of my device in use; Fig. 2 is a transverse sectional view of the same; and Fig. 3 is a side elevational view with parts broken away.

35 Referring more specifically to the drawings in which similar reference characters designate corresponding parts throughout the several views, 1 designates the sections of the hinged rail joint chair. Each rail 40 joint chair section comprises an upstanding rail web engaging portion 2 and a base portion 3 connected with the rail web engaging portion by the curved portion 4 adapted for engagement upon the upper faces of

45 the bases of the rail sections 5. Depending from the outer marginal portions of the base 3 at a point substantially central thereof are the plates 6 provided with the oppositely directed arms 7 and 8 which extend 50 inwardly beneath the base portions 3 of the members 1 and interlock, as clearly shown

in Fig. 2, and have the hinge pin 9 extended transversely through beneath the base portions, such arms 7 and 8 being of a length substantially equal to the width of the bases 55 of the rail sections 5. It will be understood that portions of the base portions 3 are cut away between the arms 7 and 8 of each hinge member 6 to accommodate the arms 7 and 8 of the other hinge member 6 thereby allowing the inner upper corners of the arms 7 and 8 to project slightly above the upper faces of the base portions 3 when the device is in open position to receive the meeting ends of the rails 5, whereby when 65 the meeting ends of the rails are placed in the chair and pressed downwardly, the inner upper corners of the arms 7 and 8 will be pressed downwardly, thereby causing said arms to swing upon the hinge pin 9 70 until the base portions 3 of the members 1 are in alinement and the upstanding web rail engaging portions 2 are engaged against the web portion of the rail sections.

The hinged rail joint chair is placed in 75 position with the hinge members 6 between two ties 10 and the ends of the sections 1 resting upon said ties. After the rail has been secured in position in the rail joint chair, said chair is secured upon the ties 80 10 by spikes 11 or other suitable means engaged in the notches 12 in the longitudinal flanges 13 of the sections 1 along the lower outer edges thereof, said spikes being properly driven into the ties 10.

85 It will be readily seen that owing to the construction of this hinged rail joint chair, the same may be readily secured upon the ties and will securely grip the meeting ends 90 of the rail sections and prevent movement of the same.

While I have shown the preferred form of my invention, it will be understood that minor changes in the details of construction may be made within the scope of the appended claim without departing from the spirit of my invention or sacrificing any of the advantages thereof.

95 What I claim is:—

In combination with the meeting ends of 100 rails, a joint chair comprising sections, each of which includes a base, a plate depend-

ing from the outer marginal portion thereof at a point intermediate its length, arms formed with such plate and base and disposed inwardly thereof, the arms of one section being adapted to interlock with the arms of the second section, such arms being of a length substantially equal to the width of the bases of the rails, and a removable

pin extending through the interlocking portions of the arms.

In testimony whereof I hereunto affix my signature in the presence of two witnesses.

JESSE MATTERN.
